UNITED STATES PATENT OFFICE

161,931

ELECTRICAL MEASURING INSTRUMENT

Paul Huber, Hillside, N. J.

Application December 31, 1948, Serial No. 150,498

Term of patent 14 years

(Cl. D52—1)

To all whom it may concern:

Be it known that I, Paul Huber, a citizen of the United States of America, residing at Hillside, in the State of New Jersey, have invented a new, original, and ornamental Design for Electrical Measuring Instruments, of which the following is a specification, reference being had to the accompanying drawings, forming part hereof, and wherein:

Fig. 1 is a front elevation of an electrical measuring instrument, showing my new design;

Fig. 2 is a side elevation of the same; and

Fig. 3 is a rear view of the same.

I claim:

The ornamental design for an electrical measuring instrument, substantially as shown.

PAUL HUBER.
